UNITED STATES PATENT OFFICE.

MARTIN HARDSCOG, OF OTTUMWA, IOWA.

ROCK DRILL.

Application filed July 2, 1923, Serial No. 648,879. Renewed November 17, 1928.

This invention relates to rock drills and has more specific reference to an improvement in the bit construction and arrangement, particularly in drills of relatively 5 large size.

The objects of this invention are, for the most part, the same as those set forth in my co-pending application filed July 2, 1923, and bearing Serial No. 648,880, this invention being directed to an application of the 10 principles of construction disclosed in said co-pending application to relatively large diameter drills.

Other objects and advantages of the 15 invention will be apparent as it is better understood from the following description, which, taken in connection with the accompanying drawings, discloses a preferred embodiment thereof.

20 Referring to the drawings,

Figure 1 is a side elevation of a rock drill embodying my invention, the same being shown in operative position in a drill hole;

25 Fig. 2 is an enlarged vertical section of the lower part of the drill bar and the blade carrying socket member;

Fig. 3 is a horizontal section taken substantially on the line 3—3 in Fig. 2; and

Fig. 4 is a bottom plan view.

30 As thus illustrated, the drill comprises an elongated bar 21 secured at its upper end in a holding member 22, which is positioned in the casing of a pneumatic hammer 23, said drill bar carrying at its lower end a bit 25 socket member 24 in which are positioned a plurality of bits 25, these, in the present instance, being four in number and arranged at an angle of 90° with respect to each other. Compressed air is supplied through a feed 40 tube 26 to operate a pneumatic hammer. Inasmuch as the details of said hammer are, for the most part, immaterial, from the standpoint of the invention, they have not been illustrated, it being merely noted that 45 the air is controlled by suitable valve mechanism 27 and serves to operate the hammer, as well as to blow the cuttings from the bottom of the drill hole. A handle 28 is provided for lifting the drill and holding it in operative position. Suitable spring-held 50 guards 29 are positioned upon the sides of the hammer to prevent the holding member 21 and bar 22 from dropping out of the hammer structure when lifted out of the well.

55 Said drill bar is provided with a central aperture 31 through which the air is directed

and a similar aperture 32 is provided in the bit carrying member 24. Said member is formed with a shank 33 engaging in a socket 34 in an enlarged portion 35 of the drill bar 60 and may be secured in place by welding, or any other desired manner.

The bits 25 are provided with cutting edges 36 and 37 at the bottom and side respectively and are formed with enlarged 65 portions 38 adapted to tightly engage in vertical recesses 39 formed in the lower end of the member 24. The recesses 39 are of such form as to prevent lateral withdrawal of the blades, which latter may be removed 70 by being knocked out from the top.

Said blades are beveled at their inner bottom edges, as indicated at 41, and contact in such manner as to practically form continuations one of the other. 75

Eccentric apertures 42 are provided leading from the central aperture 32 to the bottom of the drill and open between the blades 25. By this construction, the air passages are free from obstruction and are unlikely 80 to be obstructed by the blades or the cuttings. It will be understood that means are provided for rotating the drill during operation so that the blades, as arranged, may form a substantially round hole. 85

A sleeve, or bucket member, 43 is positioned about the lower part of the drill bar and has its lower edge supported upon a shoulder 44 formed in the holding member 24, this being for the purpose of catching 90 and removing cuttings which fall back into the hole.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, 100 the form hereinbefore described being merely a preferred embodiment thereof.

I claim:

1. A rock drill, comprising a drill bar, and a plurality of removable cutter bits arranged at the lower end of said bar, said bits being formed with a horizontal cutting edge at the bottom and a vertical cutting edge at the side and having enlarged vertically extending portions inwardly from 110 said cutting edges adapted to be disposed within corresponding recesses in a lower

part of said drill bar to hold the bits in place and the bottom cutting edges of said bits converging in matching relation.

2. A rock drill, comprising a drill bar, 5 and a plurality of removable cutter bits arranged at the lower end of said bar, said bits being formed with a horizontal cutting edge at the bottom and a vertical cutting edge at the side and having enlarged vertically extending portions inwardly from 10 said cutting edges adapted to be disposed within corresponding recesses in a lower part of said drill bar to hold the bits in place and the bottom cutting edges of said 15 bits extending beyond said vertical enlarged portions and converging in matching relation at the center of the drill.

3. A rock drill, comprising a drill bar having a socket member formed with a plurality of substantially circular recesses extending longitudinally of the bottom of the socket member, the said circular recesses having extensions disposed radially of the socket member and formed with parallel 25 sides and opening on to the peripheral face of the socket member, the bottom of said

socket member having radially extending slots registering with the extensions of said substantially circular members and extending from the center of said socket member 30 to the periphery thereof at the bottom face of said socket member, and a plurality of bits, each having a bottom portion provided with a cutting edge, a transversely extending portion provided with a side cutting 35 edge, said transversely extending portion being of a cross-section to exactly fit the substantially circular recesses and radial extensions formed in said socket member.

4. A rock drill, comprising a drill bar 40 having a socket member, the bottom face of the socket member being provided with radial slots converging to the center thereof, said slots having parallel faces and a portion of each slot having an enlargement extending transversely thereto and longitudinally of the socket member, and a bit for each slot having a cross-section corresponding to the slot and enlargement, whereby the bit may be inserted in the bottom socket 45 and held from lateral displacement.

MARTIN HARDSOCG.
